UNITED STATES PATENT OFFICE.

ERNEST N. HUMPHREY, OF NEW BRITAIN, CONNECTICUT, ASSIGNOR TO THE TRAUT & HINE MANUFACTURING COMPANY, OF NEW BRITAIN, CONNECTICUT, A CORPORATION OF CONNECTICUT.

PEN AND PENCIL HOLDER.

1,072,730.

Specification of Letters Patent.

Patented Sept. 9, 1913.

Application filed June 2, 1913. Serial No. 771,215.

To all whom it may concern:

Be it known that I, ERNEST N. HUMPHREY, a citizen of the United States, residing at New Britain, Hartford county, State of Connecticut, have invented certain new and useful Improvements in Pen and Pencil Holders, of which the following is a full, clear, and exact description:

This invention relates to a particularly advantageous form of supporting and holding means for pencils, pens and similar articles of a type wherein a clip is provided for attaching the holder to the edge of a pocket or similar supporting means.

Specifically, the invention provides a device of this character which may be advantageously formed of a single piece of sheet metal and which not only securely holds the device in position, but securely holds and maintains the article supported thereby in its initial position in the holder.

A preferable embodiment is described in detail in the following specification, taken in connection with the accompanying drawings illustrating such a preferable embodiment, and in which—

Figure 1 is a view in elevation showing the device applied to a pocket edge and with a pencil carried thereby. Fig. 2 is a rear elevation of the attachment detached from the pocket. Fig. 3 is a similar view in front elevation. Fig. 4 is a vertical section through the attachment.

Referring to the drawings by numerals, 1 indicates a pencil or analogous article adapted to be supported by the attachment, and 2 the edge of a pocket by which the attachment is supported. The attachment itself is preferably stamped from a single piece of sheet metal to provide a U-shaped supporting clip having oppositely disposed arms 3 and 4. Arm 3 of this clip, which, as illustrated, forms the outer of the two arms with reference to the pencil, is provided with a curved lower end 5 to facilitate the attachment of the clip to the pocket. This same arm is slotted to provide the elongated opening 6 therein. The opposite arm 4 is provided with a spring tongue 7 which may be struck from the material of said arm and which is in alinement with the slot 6.

From the lower extremity of arm 4 of the clip and at opposite edges thereof, spaced

spring arms 9 and 10 extend outwardly and in a plane substantially parallel with said arm. These arms diverge from the point of junction with the arm 4 of the spring clip and have their upper extremities united by a bar 11 integral therewith and spanning said arms. This bar is concaved and offset from the plane of said arms and is designed to engage the pen or pencil to hold the same against the face of arm 4 of the spring clip. These arms 9 and 10 are spaced laterally from the face of the arm 4 of the spring clip, which face, at its lower end, is recessed as at 8 to increase the resiliency of the arms and to provide clearance for the pen or pencil at that point when the upper end of the pencil is moved outwardly against the spring clamping action of the spanning bar 11. The arms 9 and 10 are spaced apart a sufficient distance to allow the insertion therebetween of the supported pen or pencil. As the spanning bar 11 is offset outwardly from the face of these arms, they will lie at opposite sides of the pen or pencil and will guide the same therebetween when the pencil is inserted, and will serve to maintain the pencil in its inserted position afterward.

The supporting U-shaped clip may dispense with the spring tongue 7 and slot 6 and engage the supporting portion of the clothing by the inherent resiliency of its arms 3 and 4, but I prefer to use said tongue and slot inasmuch as the pressure of the spring tongue serves to press the edge of the pocket, for instance, within the slotted portion 6 and thereby affords a more efficacious grip.

The entire device may be, and preferably is, formed from a single piece of sheet metal shaped by suitable mechanism to provide the structure disclosed. The specific structure disclosed is, therefore, of particular advantage from the standpoint of manufacture as well as from the standpoint of utility. The guiding action of the spring arms is also very efficacious in that it maintains the pen or pencil in a substantially vertical plane and against movement relative to the holder.

While I have herein described and illustrated a preferable embodiment of the invention, it will, of course, be understood that the same is susceptible of variation in

structure and in the relative arrangement of parts within the spirit of the invention and the scope of the appended claims.

What I claim, therefore, and desire to secure by Letters Patent is:

1. A device of the character described embodying a sheet metal U-shaped clip arranged to engage a suitable support between its arms, integral spaced spring arms extending outwardly from the end of one of said clip arms and thence backwardly in a plane substantially parallel with said clip arm, said arm being recessed at its end and intermediate the junction therewith of said spring arms to provide a clearance space, and said spring arms being united at their ends by an integral offset spanning bar arranged to engage and yieldingly clamp a pencil against said clip arm, said spaced spring arms being arranged to guide the sides of a pencil therebetween.

2. A device of the character described, embodying a sheet metal U-shaped clip having one arm slotted and having an alined spring tongue extending from its other arm and toward said slot, said clip being arranged to engage a suitable support between its arms, integral spaced spring arms extending outwardly from the end of one of said clip arms and thence backwardly in a

plane substantially parallel with said clip arm, said spring arms being united at their ends by an integral offset spanning bar arranged to engage and yieldingly clamp a pencil against said clip arm, said spaced spring arms being arranged to guide the sides of a pencil therebetween.

3. A device of the character described, embodying a sheet metal U-shaped clip having one arm slotted and having an alined spring tongue struck from its other arm and extending toward said slot, said clip being arranged to engage a suitable support between its arms, integral spaced spring arms extending outwardly from the end of one of said clip arms and thence backwardly in a plane substantially parallel with said clip arm, said arm being recessed at its end and intermediate the junction therewith of said spring arms to provide a clearance space, and said spring arms being united at their ends by an integral offset spanning bar arranged to engage and yieldingly clamp a pencil against said clip arm, said spaced spring arms being arranged to guide the sides of a pencil therebetween.

ERNEST N. HUMPHREY.
